UNITED STATES PATENT OFFICE.

MARIA A. GILLILAND, OF WASHINGTON, DISTRICT OF COLUMBIA.

RAIL-TIE.

1,179,820.

Specification of Letters Patent. Patented Apr. 18, 1916.

Application filed April 16, 1915. Serial No. 21,745.

To all whom it may concern:

Be it known that I, MARIA A. GILLILAND, a citizen of the United States, residing at Washington, in the District of Columbia, 5 have invented new and useful Improvements in Rail-Ties, of which the following is a specification.

The present invention relates to improvements in rail ties and means for securing the 10 rails to the ties.

In carrying out my invention, it is my purpose to construct a tie from a single strip of suitable metal, which shall be simple in construction, strong and durable in operation, and which shall possess a sufficient amount of resiliency to effectively cushion the rails, thus preventing breakage of the tie or of the rails under the strain incident to the weight of rolling stock imparted 20 thereto. I also aim to construct a metal tie in such a manner that when the same is arranged within the road bed the danger of sinking is reduced to a minimum and the danger of longitudinal or lateral movement will be entirely obviated. 25

It is a still further object of my invention to provide a metallic railroad tie having a hollow body portion that is substantially triangular in cross section, the meeting sides of the said body, at the apex thereof, providing longitudinal abutting surfaces at right angles, forming horizontal flanges, and to further provide longitudinal movable rail receiving members or clips 35 which coact with the mentioned horizontal flanges in such a manner as to retain the same in proper parallelism and to prevent spreading or opening of the same, the securing elements for attaching the rail seats to 40 the ties being also utilized to engage one of the longitudinal edges of the base flange of the rail to retain the said rails upon the said seats.

It is a still further object of the invention 45 to construct metallic ties which will include a hollow body portion that is substantially triangular in cross section, to provide angular sides of the said body with outwardly bulging portions forming ribs, 50 likewise to provide the base or body with similar ribs which are arranged one between two of the side ribs, the said ribs co-engaging with the road bed, when the said road bed is tamped around the tie, to prevent the 55 lateral or longitudinal movement of the said

tie, and to insure a firm seating of the tie in the road bed.

With the above objects in view the invention consists in the features of construction, combination and arrangement of parts 60 hereinafter described and claimed, reference being had to the accompanying drawings.

In the drawings Figure 1 is a perspective view of a tie and rail seats therefor constructed in accordance with my invention, 65 the rails resting upon and being secured to the rail seats; Fig. 2 is a transverse sectional view approximately on the line 2—2 of Fig. 1; Fig. 3 is a detail side elevation of the same; Fig. 4 is a perspective view of one 70 of the rail seats; Fig. 5 is a view of the blank from which the tie is formed; Fig. 6 is a view of the blank from which the rail seat and clamp are formed; Fig. 7 is an end view of a tube from which the tie may 75 be constructed to accord with my invention; Fig. 8 is an end view of the tie formed from the tube illustrated in Fig. 7; and Fig. 9 is a view of a still further modified form.

In reducing my invention to practice I 80 employ a sheet or strip of metal of the desired size and thickness, the said metal being of sufficient strength to withstand the strain to which it is subjected, and at the same time embodying sufficient resiliency to yield 85 under the weight of the rolling stock and offer no abrupt resistance to the rails supported thereon when the weight of the said rolling stock is upon the rails. By a suitable stamping machine the plate, illustrated in Fig. 5 of the drawings, is subjected, first, to a pressure which bulges the same outwardly on one of its faces to provide the same with ribs hereinafter more fully referred to. A second impression from a suitable die bends the plate to provide a substantially triangular body 1. The body at the upper edge or apex thereof is extended, forming vertically projecting, longitudinally 90 extending members 2, the inner sides of which abut, and the upper edges of the said extensions 2 are bent outwardly in opposite directions, providing a tie with horizontally disposed flanges 3—3 which are arranged at a suitable distance above the body proper. The outwardly bulged portions upon the angular sides 4 of the tie, heretofore referred to, provide spaced ribs 6—6, while the outwardly bulged central portions which 95 are provided upon the base 7 of the body 100

105

110

form the same with transversely arranged ribs 8, and each of the ribs 8 is arranged intermediate of the ribs 6.

By the peculiar construction and arrangement of the tie it will be noted that when the same is arranged within the road bed and the said road bed tamped around the tie, the flat bottom 7, will prevent the sinking of the tie in the said road bed and the transverse ribs will prevent the longitudinal movement of the tie, while, when the said road bed is tamped around the inclined sides, the peculiar formation of the said sides in connection with the ribs 6 will assist in preventing the said longitudinal movement and also prevent a lateral movement of the tie.

From practice it has been found that no means for connecting the abutting members 2 is necessary, but in order to retain the said members in abutting or contacting relation as well as to retain the flanges 3 in proper horizontal position or alinement, and further to provide means for securing the rails 9 upon the tie, I employ rail seats indicated by the numeral 10. These seats, as illustrated in Fig. 4 of the drawing, are also formed from a single piece or strip of suitable metal and are stamped to provide a horizontally straight body 11, which has one of its ends formed with an inturned angular flange 12, the said flange overlying the body and corresponding or agreeing with the inclined upper surfaces of the base flanges 13 of the rails 9, and the flange 12 is adapted to frictionally contact with the said base flange upon one of the sides of each of the rails 9. The longitudinal edges of the body 11 of each of the combined seat and clamps 10 form right angular depending flanges 14, the ends of which extend inwardly, also at a right angle, as indicated by the numeral 15. The flanges are arranged away from but are in a parallel line with the under face of the flat body 11. The right angular flanges 14, and the horizontal flanges 15, are so arranged that the same, when inserted longitudinally from the opposite ends of the horizontal flanges 3 of the tie proper, will frictionally contact with both the outer longitudinal edges of the said flanges or head portions 3 as well as with the other faces of the same. It will be noted that the members 10 effectively retain the flanges 3 against spreading. The vertical portions 2 are primarily provided to permit of the arrangement of the nuts 15 between the flanges 3 and the inclined sides 4 of the hollow body of the tie, while bolts 16 have their shanks passed through suitable openings in the body 11 of the members 10 as well as through openings in the flanges 3 and are engaged by the said nuts 15. The heads of the bolts 16 contact with the base flanges of the rails 9 opposite the portions

of the said base flanges engaged by the flanges 12 of the members 10.

In Fig. 7 I show a tube which may be placed upon a suitable rolling machine to produce a tie similar to that illustrated in Fig. 8 of the drawings.

In Fig. 9 I have illustrated a still further modified form of my improvement. The structure disclosed in this figure is formed from a single sheet or strip of suitable metal 75 and includes a triangular body A which has its sides formed with vertical extensions B, the said extensions having their ends flanged outwardly in opposite directions, as indicated by the characters C. The horizontally straight portions C are bent upon themselves as indicated by the characters D, and the portions C and D provide the upper face or head of the tie. The ends of the portions D are bent downwardly, as at E 85 between the vertical members B, and contact with each other as well as with the inner faces of the said members B. The portions E are provided with angular extensions F, the same diverging in opposite 90 directions from their contacting portions and the ends of the said members F rest upon the base of the substantially triangular body A. By spreading the legs or angular members F it will be noted that the 95 resiliency of the head D is not materially affected, and the slideable rail receiving members or seats, heretofore referred to, engage with the longitudinal edges of the face or head of the tie as well as rest directly upon the upper surface of the said head, and securing nuts and bolts, similar to those previously described, are employed for locking the rail seats to the head. The head being of a double thickness is, it will 100 be noted, materially strengthened, and the sides as well as the base of the body may be provided with the ribs described in connection with Figs. 1 to 5.

Having thus described the invention, what I claim is:

1. A tie formed of a single sheet of metal, stamped to provide a substantially triangular body, the meeting edges of which being extended to provide abutting surfaces, and the said surfaces having their ends flanged outwardly in opposite directions to form the top of the tie, a rail seat having its longitudinal edges flanged to provide ways, said seat having one of its ends provided with an angular flange forming a rail engaging lip, the seat adapted to be arranged upon the top for longitudinal movement and have its longitudinal flanges engage with the longitudinal edges of the underfaces of the face of the tie, means for securing the seat upon the face of the tie, and said means adapted to co-act with the rail, as and for the purpose set forth.

2. A metal tie formed from a single sheet 130

and including a substantially triangular body, the ends of which being extended in parallel relation and being flanged in opposite directions parallel with the base of the body, said flanges being bent upon themselves and lapped to provide a head for the tie of a thickness twice as great as that of the seat, the said lapped portions having their ends extended toward the base between the extending portions of the meeting ends of the base and contacting with each other and with the said extending portions of the base, the said contacting portions being further extended divergently and contacting with the base.

3. A metal tie formed from a single sheet and bent to form a triangular body, the base portion of the body as well as the angular sides thereof being depressed to provide outwardly projecting ribs and the ribs of the base being disposed intermediate of the ribs of the sides, said sides having their meeting ends extended vertically to provide abutting surfaces and the edges of the said

surfaces being bent in opposite directions to provide the tie with auxiliary straight flanges, a rail seat having its opposite edges bent and formed with inturned portions positioned upon the flanges, whereby the edges and the underfaces of said flanges will engage the inturned portions of the rail flanges to prevent the bending of said rail flanges, each of said rail seats having one of its edges formed with a transverse lip which is adapted to engage with one of the edges of the flange of a rail, securing elements passing through each of the seats and through the flanges of the tie, said securing elements contacting with the longitudinal edge of the rail flange opposite that engaged by the lip, and means for securing the said elements upon the flanges of the tie.

In testimony whereof I affix my signature in presence of two witnesses.

MARIA A. GILLILAND.
